UNITED STATES PATENT OFFICE.

FLOYD AUGUSTUS CANTWELL, OF IRVING, KANSAS.

CIRCUIT CONTROLLER.

Application filed September 22, 1920. Serial No. 412,080.

To all whom it may concern:

Be it known that I, FLOYD A. CANTWELL, a citizen of the United States, and a resident of Irving, in the county of Marshall and State of Kansas, have invented certain new and useful Improvements in Circuit Controllers, of which the following is a specification.

The present invention relates in general to 10 circuit controllers, and more particularly to a circuit controller especially adapted to be associated with and operated by the mechanism of a switch stand.

The object of the invention is to provide 15 a circuit controller of this character which is incorporated in the circuits of the block signalling or similar system, and which opens or closes these circuits in accordance with the position of the mechanism of the switch stand and thus affords, at distant 20 points, a proper indication of the condition of the switch controlled by the mechanism of the switch stand.

Another object of the invention is to provide 25 a device of this character of simple and durable construction, reliable in operation and easy and inexpensive to manufacture and apply.

Other objects and advantages reside in 30 the certain novel features of the construction, arrangement and combination of parts which will be hereinafter more fully described and particularly pointed out in the appended claims, reference being had to the 35 accompanying drawings forming part of this specification, and in which—

Figure 1 is a plan view of the invention associated with the switch stand;

Figure 2 is a front elevational view there- 40 of;

Figure 3 is a perspective view of the circuit controller, the casing being broken away for the purpose of illustration;

Figure 4 is a detail perspective view of 45 a modified form of contact engaging element;

Figure 5 is a diagrammatic view of the general type of circuits adapted to be controlled by one of the sets of contacts of the 50 circuit controller;

Figure 6 is a similar view of the circuits controlled by the other set of contacts.

Referring to the drawings, it will be seen that the invention is associated with the mechanism of a switch stand or the like. 55 The switch stand is preferably of the

character forming the subject matter of my co-pending application Serial No. 348,737, and includes a table 10 having spaced peripheral notches 11 and 12 formed therein. 60 A vertical shaft 13 is journaled in the table and is controlled by a switch lever 14 secured thereto. The outer end of the switch lever carries the drop or lock arm 15 which is adapted to be swung into either the notch 65 11 or the notch 12. A target 16 is carried at the upper end of a sleeve 17 which, in turn, is carried by a spool 18 and a target lever 19 co-acts with the spool 18 to control the target. When the switch lever 14 is moved to the extreme left and the lock arm 15 is swung into the notch 11 and the target lever 19 is superposed upon and interlocked with the switch lever and lock arm, the switch is locked set for main line 70 75 and the target is in position to indicate "Safety" or "Clear." In all other positions and at all times except when the switch is thus locked set for main line the target indicates "Danger." 80

The circuit controller is designated generally at 20 and is positioned on the table adjacent the notch 11, as clearly shown in plan in Figure 1. The circuit controller consists of a casing 21 having a lower laterally extending flange 22 adapted to be secured, as at 23, to the table. The casing 21 is weather-proofed and insulated. A pair or set of upper contacts 24 is carried in the upper part of the casing adjacent one end thereof and a pair or set of lower contacts 25 is carried in the lower part of the casing at the same end. Each pair of contacts consists of two spring contacts 26 which are carried by a bracket 27 adjustably secured, as at 28, to the inner wall of the casing. Each of the spring contacts 26 is insulated from the bracket by means of insulation 28. These contacts are normally spaced so as to normally break or open the circuit in 100 which they are incorporated.

Operating means is provided for the circuit controller and consists of an operating shaft 29 journaled, as at 30, in the side wall of the casing and also journaled within the casing in a suitable bearing provided in the lug 31. The journal 30 is also provided with a conventional stuffing box or the like to render the casing entirely weather-proof. The inner end of the operating shaft 29 carries an operating arm 32 which is fixed to the shaft and constrained

2
to rotate therewith. A nut 33' is employed to retain the operating arm on the shaft. The outer end of the operating arm is enlarged, as indicated at 32^a. A contact engaging element 33 adapted to co-operate with the upper pair or set of contacts 24 and a contact engaging element 34 adapted to co-operate with the lower pair or set of contacts 25 are each carried by the enlarged portion 32^a of the operating arm. These contact engaging elements are identical in construction and they are each provided with an insulated tip 33^a and 34^a, respectively. The body of each contact engaging element is longitudinally slotted, as indicated at 33^b and 34^b and screws 33^c and 34^c extend through the slots of the respective elements and are seated in the underlying portion of the operating arm to provide for adjustment of each of the contact engaging elements and their retention in adjusted position.

Spring means is provided for biasing the operating shaft 29, preferably so as to throw the operating arm upwardly with the contact engaging element 33 maintaining the upper pair of contacts 24 closed or engaged, and with the contact engaging element 34 out of engagement with the lower pair of contacts 25 so as to leave the spring contacts of this latter pair open. This spring means consists of a blade spring 35 having one end seated in a slot 29^a provided in the operating shaft 29 and having the other end resting upon a carrier 36 adjustably secured to the interior of the side wall of the casing by means of a longitudinal slot 36^a provided in the carrier and adjusting screws 36^b operating through said slot. An adjustable abutment 37 engages and bows the blade spring intermediate the operating shaft and the carrier, so that the blade spring is normally under tension, tending to maintain the operating arm upwardly inclined, with the contact engaging element 33 engaging the spring contacts 26 of the upper pair 24, as shown in Figure 3.

A crank arm 38 is integral or otherwise connected with the operating shaft 29 and extends exteriorly of the casing, as shown in Figures 1 and 2. The outer end of the crank arm carries a set screw 39 adjustable with respect to the crank arm. The set screw is adapted to be engaged by the lug 19^a which is formed on and extends laterally of the target lever 19.

As shown in the drawings, the parts are so positioned that when the target lever is swung in a clockwise direction so as to be superposed on the switch lever which has its lock arm resting in the notch 11 and the target lever is dropped into interlocking relation with the switch lever and lock arm, the lug 19^a engages the set screw 39 and depresses it. This depression of the

set screw carries with it the crank arm and the operating shaft against the tension of the blade spring 35. The operating shaft is thus rotated in a clockwise direction and swings the operating arm 32 downwardly so that the contact engaging element 33 releases the contacts 26 of the upper pair 24 and the contact engaging element 34 engages the contacts 26 of the lower pair and moves them into engagement to close the circuit in which they are incorporated.

In lieu of the adjustable contacts 33 and 34 shown in Figure 3, a single double acting contact engaging element may be provided, as shown in Figure 4, and consists simply of a short rod 40 adapted to be adjustably positioned in the outer end of the operating arm 32 and to be secured in adjusted position by means of the set screw 41.

The circuit controller is adapted to be incorporated in the circuits of any standard or conventional block signalling or similar system and for this purpose each of the contacts 26 of both the upper pair 24 and the lower pair 25 is provided with a binding post 42 which is adapted to electrically connect each spring contact to a conductor or lead of its respective circuit. For the sake of illustration, the invention is diagrammatically shown in Figures 5 and 6 incorporated in an elementary type of signalling system.

In Figure 5 the contacts of the upper pair 24 are shown in their closed position, in which they are held by the contact engaging element at all times except when the switch is locked set for main line. At this time the circuit is completed from the source of current 43 through the relay 44 to throw the movable contact 45 into engagement with the stationary contact 46 and thus complete the circuit from the source of current 48 through an electro-magnetic means 49 controlling the semaphore 50. The contacts 26 of the pair 24 spring apart from each other when released by the contact engaging element when the mechanism of the switch stand is locked set for main line and break the circuit through the relay 44. The retractile coil spring 51 then acts upon the movable contact 45 to throw the same out of engagement with the stationary contact 46 and break the circuit through the electro-magnetic means 49 to allow the semaphore 50 to drop to "Clear" or "Safety."

In Figure 6 the contacts 26 of the lower pair 25 are shown spaced, which is the position they occupy when the mechanism of the switch stand is positioned otherwise than locked set for main line. At this time the circuit from the source of current 52 through the relay 53 is broken, allowing the retractile coil spring 54 to throw the movable contact 55 into engagement with the stationary contact 56 and thus complete the

circuit from the source of current 57 through the electro-magnetic means 58 to thereby throw the semaphore 59 to "Danger." When the contact engaging element presses the contacts 26 into engagement the circuit to the relay 53 is completed and the armature 55 is drawn by the relay out of engagement with the stationary contacts 56, thus breaking the circuit through the electro-magnetic means 58 and permitting the semaphore to fall to "Clear."

I claim:

1. In combination with the mechanism of the switch stand including a lever having a laterally extending lug, a circuit controller comprising an upper pair of normally spaced spring contacts, a lower pair of normally spaced spring contacts, and operating means for moving the contacts of either pair into engagement, consisting of an operating shaft, an operating arm carried on the inner end of the operating shaft, an adjustable contact engaging element for each pair of contacts carried by the outer end of said operating arm, spring means engaged with the operating shaft for biasing the contact engaging elements, and a crank arm connected with the operating shaft and engaged by the lug of the lever whereby the circuit controller is operated by the mechanism of the switch stand.

2. In combination with the mechanism of a switch stand including a lever having a laterally extending lug, a circuit controller comprising a pair of normally spaced spring contacts, and operating means for moving the contacts into engagement, consisting of an operating shaft, an operating arm carried by the shaft, an adjustable contact engaging element carried by the operating arm, spring means engaged with the operating shaft for biasing the contact engaging element, and a crank arm fixed to the operating shaft and adapted to be engaged by the lug of the lever of the switch stand

35

40

3. A circuit controller comprising a casing, a pair of spring contacts therein and operating means for the spring contacts consisting of an operating shaft journaled in the casing and having a slot therein, an operating arm carried on the inner end of said operating shaft, an adjustable contact engaging element carried by the outer end of said operating arm, a blade spring 55 carried by the casing and having one end seated in the slot of the shaft to bias the contact engaging elements, and a crank arm fixed to the operating shaft exteriorly of the casing and adapted to move the shaft 60 against the action of said spring.

FLOYD AUGUSTUS CANTWELL.
